CLAIM

The ornamental design of a telephone station, as shown and described.

DESCRIPTION

FIG. 1 is a perspective view taken from the top right side of a telephone station having twelve programmable keys or buttons with a telephone handset being removed;

FIG. 2 is a top plan view of the telephone station of FIG. 1; FIG. 3 is a bottom plan view of the telephone station of FIG. 1;

FIG. 4 is an elevational view of the right side of the telephone station of FIG. 2;

FIG. 5 is an elevational view of the left side of the telephone station of FIG. 2;

FIG. 6 is a front elevational view of the telephone station of FIG. 2;

FIG. 7 is a rear elevational view of the telephone station of FIG. 2;

FIG. 8 is a perspective view taken from the top right side of a modification of the telephone station of FIG. 1 having nineteen programmable keys;

FIG. 9 is a top plan view of the telephone station of FIG. 8; FIG. 10 is a bottom plan view of the telephone station of FIG. 8;

FIG. 11 is a side elevational view of the right side of the telephone station of FIG. 9;

FIG. 12 is a side elevational view of the left side of the telephone station of FIG. 9;

FIG. 13 is a rear elevational view of the telephone station of FIG. 9;

FIG. 14 is a front elevational view of the telephone station of FIG. 9; and,

FIG. 15 is a perspective view taken from the top right side of a modification of the telephone station of FIG. 8 having an enlarged display.

Except for the enlarged display, the portions of this embodiment that are not shown are the same in appearance as the second embodiment, FIGS. 8-14.
